UNITED STATES PATENT OFFICE.

SAMUEL B. PACK, OF WASHINGTON, DISTRICT OF COLUMBIA, ASSIGNOR TO PACKMORE MANUFACTURING COMPANY, A CORPORATION OF DELAWARE.

PORTABLE CLEANING-MACHINE.

1,339,280.

Specification of Letters Patent.

Patented May 4, 1920.

Application filed June 15, 1912. Serial No. 703,908.

To all whom it may concern:

Be it known that I, SAMUEL B. PACK, a citizen of the United States, residing at Washington, in the District of Columbia, have invented certain new and useful Improvements in Portable Cleaning-Machines, of which the following is a specification.

This invention relates to vacuum cleaning apparatus, and particularly to that type in which the suction-creating means are operated by the handle that serves as the means for propelling the apparatus, the usual backward and forward movement imparted to the apparatus in use serving to 15 vibrate the lever and thus work the suction-creating means.

The primary object of the invention is, first to reduce to practical commercial form a self-contained manually operated pneumatic cleaning machine of the type just referred to where the propelling handle serves as the means for operating the suction device, and secondly, to simplify the construction of portable suction cleaning machines generally where bellows or diaphragm pumps are employed by minimizing the number of parts, and rendering such machines more durable and economical to manufacture. To this end, I provide a pecu- 20 liar form of casing or body adapted to contain the dust drawn into the machine, and to also hold a diaphragm of unusual size in a peculiar and durable manner, and which serves as the suction-creating device.

Another special object has been to make such machines small and compact, and yet provide an ample and substantial suction-creating means.

Another special object of my invention 40 has been to devise a machine embodying a cleaning mechanism of the vacuum or suction class and also of the brush or agitating type. In carrying out this feature of the invention, the brush cleaner is so mounted on 45 the body or casing of the machine, that the latter may be propelled readily without effective operation of the brush element, though the suction cleaner is actuated, a mere variation in the pressure exerted upon 50 the handle by the operator resulting in an adjustment of the suction head or nozzle of the machine, to thereby cause a combined

action of the suction and brush cleaning devices. In this way, the efficient operation of the invention may be controlled at will 55 by the operator to produce the best results or, in other words, only such action of the cleaning means as may be necessary under different conditions of service, for, as is well known, there are times when the suc- 60 tion cleaner alone is ample for complete cleaning purposes.

Still another, but minor object of my invention has been the provision of a special carrier for the dust bag or receptacle and 65 which has thereon a suction controlling valve adapted to be removed along with the carrier for purposes of repair, or the like, and to afford access to interior parts of the machine.

Among other features of novelty of my present improvements are the use of a peculiarly mounted diaphragm as part of the suction creating devices, adapted for single or double-acting functions in respect to 70 causing a suction through the nozzle of the machine, an advantageous relative mounting of the operating handle and said diaphragm to derive simultaneous operation of the same, and the provision of conveniently operable 75 means for holding the various parts of the machine in proper operative positions.

In the accompanying drawings, Figure 1 is a side elevation of a suction and brush cleaning machine embodying the essential 80 features of the invention, the operating handle being broken away.

Fig. 2 is a front elevation of the same.

Fig. 3 is a bottom plan view.

Fig. 4 is a longitudinal sectional view.

Fig. 5 is a horizontal sectional view taken on the line 5—5 of Fig. 4.

Fig. 6 is a detail perspective view of the removable dust bag holder and valve carrier.

Fig. 7 is a view similar to Fig. 4, showing a modified embodiment of the machine wherein the suction creating diaphragm is double-acting.

Throughout the following detail description and on the several figures of the drawings, similar parts are referred to by like reference characters.

In the drawings, the body or casing of the machine is denoted at A and is a hollow

structure composed of the upper section 1 and the lower section 2. The sections 1 and 2 are provided at their adjacent edges with flanges 3 through which fastenings 4 pass, 5 the latter firmly but detachably connecting the sections together. The body A is supported upon the rearmost wheels or rollers 5, the intermediate wheels 6 and the suction head or nozzle 7 located at the front 10 end of the machine and telescopically as well as yieldingly connected with a coupling head 8 attached to the front end portion of the body A and carried by the section 1 of the latter. The nozzle 7, so far as the present invention is concerned may be of any conventional type. As illustrated it has telescopic connection with the coupling head, and a coiled spring 9 is interposed between the parts, 7 and 8, tending to separate them and operating to hold the nozzle in yielding engagement with the floor or other surface to be cleaned. A catch 10 secured to the coupling head 8 engages at its lower end with a lug 11 on the nozzle 7 and 15 limits the downward movement of said nozzle, and an interlocking connection is provided between the nozzle and the lower front portion of the body A consisting of the flange 7' and U-shaped lug 7'', the 20 former projecting rearwardly from the nozzle.

The coupling head 8 comprises a tubular body, the lower portion of which, 8'', fits into the upper tubular extension of the nozzle, and a plate 8' to fit against and close an opening formed in the front end of the section 1 of the body A. Fitting in the uppermost portion of said section 1 is the dust bag holder and valve carrier 12, consisting of a receptacle which tapers toward its inner end and has at its outer open end a rim 12', as shown clearly in Fig. 6, said rim fitting snugly against the edge of the front opening of the section 1 and being 35 clamped in such position to hold the carrier properly in place in the body A by means of a locking bail 13. The bail 13 is pivoted to the body A as shown at 13' and its cross bar is adapted to directly engage 40 with the cams 14 formed on the outer side of the plate 8' of the coupling head, whereby to tightly clamp the latter along with the part 12 in the position shown in Fig. 4. The plate 8' of the coupling head is in 45 direct engagement also with the outer end 15' of the frame 15'' of the dust bag 15, the latter being adapted to fit snugly within the holder or carrier 12 and having its open end in communication with the hollow portion 50 of the coupling head 8 so that the dust or foreign matter drawn into the nozzle will pass readily to the dust bag 15 in a manner which will be described more fully herein- 55 after. At the inner extremity of the part 60 12 is a valve 16 arranged to open and close

apertures or openings 17 provided in the end plate of the part 12.

Beneath the holder 12 and within the body or casing A of the machine is arranged the suction creating device 18 which consists of a diaphragm composed of a metal body and flexible portions 18' connecting the body with the casing A, the free edges of said flexible portions 18' being clamped between the flanges 3 of the sections 1 and 2 of the casing so that an air-tight connection between the diaphragm and the casing is thus obtained. The diaphragm is connected at its front end with a pivot member 19, the ends of which are journaled in 70 and project through bearings in the sides of the section 2 of the casing A and said ends or extremities are of a form to interlock with correspondingly shaped openings in the ends 21 of the bail or fork 20 which 75 constitutes the lower section or portion of the handle 21. The diaphragm 18 therefore has a pivotal or swinging movement in the casing A and near the free end portion of the diaphragm are formed a plurality of 80 openings or apertures 22, which are normally closed by the valve 23. The arrangement of the diaphragm H within the casing A as shown is advantageous since it forms spaces or chambers respectively above 85 and below the said diaphragm, the upper space receiving certain parts hereinbefore described and the whole arrangement being conducive to the production of a minimum sized casing or body for the machine. The 90 bottom section of the casing A is formed with downwardly projecting hollow extensions 2' in the sides of which are journaled the axles 24 of the wheels 6, said axles being arranged in slotted bearings and being 95 engaged by springs 25 whereby the casing is yieldingly mounted upon the wheels 6. Pivoted pans 26 are carried by the extensions 2' of the casing and intermediate the extensions 2' and pans 26 is mounted the 100 cleaning or sweeping brush 27, journaled in brackets 28 of the casing A. Said brush 27 is adapted to perform the function of the brush of an ordinary carpet sweeper but is normally maintained in a position in which 105 it only has a very light contact with the surface traversed by the machine or none at all, by means of the spring pressed, yielding suction nozzle 7 and the wheels 6 which are located at the opposite sides of the 110 brush. If desired, the dust bag holder and valve carrier 12 may have the rim 12' thereof notched, as shown at 12'', to interlock with a lug 29 formed on the front extremity of the casing A to assist the operator in 115 properly positioning the part 12 after once removing the same. In operating with a machine such as described the suction-creating devices are worked as the casing is moved backward and forward, the pivot 120

125

130

member 19 being common to the diaphragm 18 and to the handle 21 so that as the machine is worked back and forth over a carpet, rug, or other surface to be cleaned, the 5 operator will naturally impart to said handle an up and down movement. Said up and down movement of the handle 21 causes the same to act as a lever, and imparts to the diaphragm 18 an up and down movement, 10 a suction being created through the head 8, bag 15 which is of porous material, and valved openings 17, during the downward movement of the diaphragm. As the diaphragm 18 moves upwardly, the valve 15 15 opens and as the diaphragm moves downwardly, said valve closes, any air previously drawn into the lower portion of the casing A beneath the diaphragm being expelled from the casing A in the downward movement 20 of said diaphragm through a suitable valved opening 30. Should the operator desire to utilize both the suction and brush cleaning means, a greater pressure than ordinarily used would be exerted upon the handle 21, whereupon the suction nozzle 7 and wheels 6 will yield upwardly to such 25 an extent that the brush 27 will engage the surface operated upon for effective cleaning action simultaneous with the suction cleaning action obtained through said nozzle. It 30 may be noted that the location of the point of connection of the handle 21 with the front end of the machine and at a point intermediate the nozzle 7 and brush 27 is important 35 in controlling not only the operation of the suction device but in facilitating the application of pressure at the proper portion of the casing of the machine to regulate the combined operation of the vacuum 40 and brush cleaning instrumentalities.

When the dust bag 15 is ready to be emptied, the operator simply raises the locking bail 13 and detaches the coupling head 8 with its nozzle 7, the dust bag being 45 then accessible for removal from the part 12. The part 12, of course, will only be removed when it is desired to have access to its valve 16, or to the diaphragm 18 and other interior parts of the casing A.

50 In the modification of the invention shown in Fig. 7, the general construction previously described is followed quite closely except that an inclined partition 31' is provided in the upper section 1' of the 55 casing and the dust bag holder and valve carrier 12 is dispensed with. In this construction also, the diaphragm 18 is double-acting or adapted to create a suction through the nozzle, both on its upward and 60 downward movements, for which purpose a suction valve 32 is provided to control openings in the partition 31', and a second suction valve 33 is provided to control openings at the front extremity of the lower section 65 2' of the casing A'. A by-pass 34 leads

downwardly in the front end of the casing A' from the inner extremity of the coupling head 8 and at a point beneath the dust bag 15. Suitable outlet valves 35 and 36 are provided for the sections 1' and 2', respectively, of the casing A' and are located at the rear end of the machine at points respectively above and below the diaphragm 18. On upward movement of the diaphragm by the handle 21, suction is created from 70 beneath the diaphragm through the by-pass 34 and the openings controlled by the valve 33, while on the downward movement of the diaphragm, suction is created through the valved openings of the partition 31'. Parts 80 used in the modification of Fig. 7 and which are substantially the same as employed in the previously described construction, are numbered similarly to the parts of the latter. 85

It will be seen that in both forms of the invention thus far described there are two compartments in the casing, in one of which is located the filter or dust bag, and in the other the movable diaphragm connected at 90 its edges with the walls of the casing; and that the compartment in which is located the dust bag tapers toward the rear while the other compartment tapers toward the front, the pivot about which the diaphragm 95 turns being located in the forward and narrow portion of the compartment containing the pumping diaphragm. This is a very desirable arrangement for several reasons. In the first place it utilizes the capacity of 100 the casing to great advantage, since the end of the dust bag that communicates with the nozzle head should be large and the flaring or large end of the compartment in which it is located is, in the constructions described, toward the front. Again, that portion of the diaphragm which is toward the rear requires much more space for its movements than does its pivoted end, and hence the latter can be located to advantage in 110 the tapering end of the pump compartment. And, further still, it is of advantage to have the rock shaft constituting the pivot of the oscillating diaphragm, to which the handle 21 is connected, well toward the front of the 115 machine, as has been stated, and this is secured in the arrangement being described.

In the operation of the invention as a combined suction and brush cleaner, it will be apparent that the front sweeper wheels 120 and nozzle 7 will yield to a greater extent than the rear sweeper wheels 6, when pressure is exerted upon the handle 21 to bring the brush into action.

I do not in this application claim the operation of the suction-creating devices in a portable carpet cleaner such as illustrated herein, by a pivoted vertically swinging handle that is employed for propelling the machine back and forth over the carpet, as 125 130

that subject matter is presented and claimed in another application filed by David P. Moore and myself as joint inventors on the 29th day of January, 1910, and 5 bearing Serial No. 540,795.

Having thus described the invention, what is claimed as new is:

1. In a portable floor-cleaning machine, a wheel-supported casing carrying a suction 10 nozzle, a pump diaphragm pivotally supported near one end of the casing and having marginal flexible portions that are secured to the two sides of the casing and to that end which is opposite the end at which 15 the diaphragm is pivotally supported, the diaphragm dividing the closed chamber of the casing into two compartments, and being perforated and valved, and the casing having an inlet passage from the nozzle to 20 a compartment on one side of the pump diaphragm and an outlet passage from the compartment on the other side of the diaphragm, and means for vibrating the diaphragm up and down as the casing is moved 25 over the floor surface being cleaned.
2. A portable suction cleaning machine, comprising a casing supported so as to be easily moved over a surface to be cleaned, a suction nozzle carried by the casing, a diaphragm pivotally mounted within the casing and having two of its side margins and 30 one end margin flexible and fastened to the said casing, and a single handle for propelling the machine over the surface to be cleaned having operative connection with 35

the diaphragm whereby it is actuated as the machine is moved by the handle.

3. In a suction cleaning machine, a suction-creating device comprising a casing supported so as to be easily moved over a surface being cleaned and formed of two sections, a suction nozzle carried by the casing, a valved diaphragm pivotally mounted within the casing and having flexible marginal portions at its two sides and one end 40 connected with the casing, a handle for propelling the casing over the surface to be cleaned, and a pivot common to the handle and the diaphragm, the handle being secured thereto so that it and the diaphragm 45 are operatively connected, whereby the vibratory movements of the handle as the machine is moved in operation actuate the said diaphragm.

4. In a portable cleaning machine, the 55 combination of a casing supported so as to be easily moved over a surface being cleaned, a suction nozzle carried by the casing, a pivoted suction-creating diaphragm mounted within the casing, a handle for 60 propelling the machine, and a pivot common to the handle and the suction-creating diaphragm and to which both are secured.

In testimony whereof I affix my signature in the presence of two witnesses.

SAMUEL B. PACK.
